UNITED STATES PATENT OFFICE.

MARTHA V. JOHNSON, OF RICHLAND, MISSOURI.

ORDNANCE.

1,289,185.

Specification of Letters Patent. Patented Dec. 31, 1918.

Application filed August 10, 1918. Serial No. 249,238.

To all whom it may concern:

Be it known that I, MARTHA V. JOHNSON, a citizen of the United States, residing at Richland, in the county of Pulaski and 5 State of Missouri, have invented certain new and useful Improvements in Ordnance, of which the following is a specification, reference being had to the accompanying drawings.

10 This invention relates to certain improvements in ordnance and it is an object of the invention to provide novel and improved means whereby small arms may be mounted upon a heavy gun, field piece, or the like to 15 afford protection to the squad or crew manning the gun and particularly during the intervals when the gun is being reloaded.

It is also an object of the invention to 20 provide a novel and improved means of this general character embodying a cross member adapted to be secured to the barrel of a heavy gun or the like and which extends beyond either side thereof and small arms, such as the guns used by infantry or the 25 like, are mounted upon said member together with means whereby a plurality of said arms may be discharged in unison.

The invention consists in the details of 30 construction and in the combination and arrangement of the several parts of my improved ordnance whereby certain important advantages are attained and the device rendered simpler, less expensive and otherwise more convenient and advantageous for use, 35 as will be hereinafter more fully set forth.

The novel features of my invention will 40 hereinafter be definitely claimed.

In order that my invention may be the better understood I will now proceed to describe the same with reference to the accompanying drawings, wherein:

Figure 1 is a view in top plan illustrating an embodiment of my invention;

Fig. 2 is a view partly in cross section 45 and partly in elevation, illustrating the mounting of a small arm upon the cross member as herein disclosed;

Fig. 3 is a fragmentary view partly in elevation and partly in longitudinal section, 50 illustrating in detail one of the clamps as herein employed, for holding a small fire arm to the cross member;

Fig. 4 is a fragmentary view in top plan, illustrating in detail the means herein em-

ployed for firing a plurality of small fire- 55 arms in unison; and

Fig. 5 is a fragmentary view partly in cross section and partly in elevation, illustrating the means as herein embodied for securing the cross member to the barrel of 60 a field piece or the like.

As disclosed in the accompanying drawings, B denotes the barrel of a field piece and C denotes a cross member positioned adjacent the breech of the barrel and extending beyond opposite sides thereof. As herein disclosed the cross member C is held to the barrel B by a substantially U-shaped yoke A straddling the barrel B from below and having its free extremities disposed 65 through suitable openings 1 in the cross member and engaged with end portions of the yoke A outwardly of the cross member C of the clamping nuts 2 or their equivalent, whereby the cross member C is effectively mounted upon the barrel B.

In the present embodiment of my invention the cross member C comprises two elongated strips of suitable material imposed one upon the other and suitably secured to the upper plates of the lower strip 3 is a lamination 3^a of rubber or other elastic material and with which the upper strip 4 of the cross member C directly contacts. The lamination 3^a serves as an agency 80 to absorb the vibrations or jars incident to the firing of a field piece. Extending upwardly from the strip 4 at opposite sides of its longitudinal center or of the barrel B when in applied position are the plurality 85 of clamping members 5, which are adapted to engage small arms S such as the guns employed by infantry or the like with the muzzles of said guns forwardly directed.

The guns or small arms S at opposite 90 sides of the barrel B each constitute an individual series. Arranged rearwardly of each series of guns or arms S is a rod 6 disposed longitudinally of the member C and extending forwardly from said rod 6 100 is a plurality of hook members 7 or the like which are suitably engaged with the triggers of the guns or small arms S so that upon imposing a pull upon the rod 6 the guns or arms of the coacting series will be 105 caused to fire in unison. In order to facilitate the proper pull on the rod 6 I find it of advantage to provide the same at substan-

tially its longitudinal center with a handle or hand grasp 8.

I also find it of advantage to provide the lower strip 3 of the cross member C at opposite sides of the barrel B with the rearwardly directed guide pins 9 loosely directed through the opposite end portions of the adjacent rods 6 and to interpose between said strip 3 and each of the rods 6 the retractile members 10 which serve to move the rods in a direction toward the cross member C when relieved of strain so that the firing mechanism of the guns or small arms S may properly function.

15 By mounting the guns or arms S as hereinbefore set forth it will be at once self evident that an effective defense is provided for the gun squad or crew against local attacks by the enemy and especially during the 20 intervals between discharging from the barrel B.

From the foregoing description, it is thought to be obvious that an ordinance constructed in accordance with my invention is 25 particularly well adapted for use by reason of the convenience and facility with which it may be assembled and operated and it will also be obvious that my invention is susceptible of some change and modification 30 without departing from the principles and spirit thereof and for this reason I do not wish to be understood as limiting myself to the precise arrangement and formation of the several parts herein shown in carrying 35 out my invention in practice except as hereinafter claimed.

Copies of this patent may be obtained for five cents each, by addressing the "Commissioner of Patents, Washington, D. C."

I claim:

1. In combination with the barrel of a cannon, a cross strip secured to the barrel thereof, said cross member comprising two superimposed strips, a lamination of yieldable material secured to a face of one of the strips and with which the second strip contacts and means carried by the cross member for clamping firearms thereto. 40 45

2. In combination with a cross member adapted to be secured to the barrel of a cannon and firearms mounted upon the cross member; a rod and means for connecting said rod to the firing mechanisms of a plurality of said firearms whereby said firearms may be discharged in unison upon pull on the rod, and means carried by the cross member for supporting the rod and guiding the same in its movement. 50 55

3. In combination with a cross member adapted to be secured to the barrel of a cannon and firearms mounted upon the cross member; a rod, means for connecting said rod to the firing mechanisms of a plurality of said firearms whereby said firearms may be discharged in unison upon pull on the rod, and means carried by the cross member for supporting the rod and guiding the same in its movement, and means for automatically moving the rod in one direction. 60 65

In testimony whereof I hereunto affix my signature in the presence of two witnesses.

MARTHA V. JOHNSON.
